UNITED STATES PATENT OFFICE.

EDGAR T. WINTER, OF DES MOINES, IOWA.

ACETYLENE-GAS GENERATOR.

1,108,960.

Specification of Letters Patent.

Patented Sept. 1, 1914.

Application filed October 21, 1912. Serial No. 727,022.

To all whom it may concern:

Be it known that I, EDGAR T. WINTER, citizen of the United States of America, and resident of Des Moines, Polk county, Iowa, have invented a new and useful Acetylene-Gas Generator, of which the following is a specification.

The object of this invention is to provide an improved construction for acetylene gas generators.

A further object of this invention is to provide improved construction for and means of mounting carbide cartridges in an acetylene gas generator.

15 A further object of this invention is to provide improved means for removing and replacing a carbide cartridge relative to a cartridge holder.

20 My invention consists in the construction, arrangement and combination of elements hereinafter set forth, pointed out in my claims and illustrated by the accompanying drawing, in which—

Figure 1 is a vertical section of the complete device. Fig. 2 is a vertical section at right angles to Fig. 1. Fig. 3 is a horizontal section on the indicated line 3—3 of Fig. 2. Fig. 4 is a plan of the device. Fig. 5 is a vertical section of a carbide cartridge, 25 cartridge holder and shell detached. Fig. 6 is an elevation partly in section illustrating a carbide cartridge and cartridge holder mounted on a removing frustum. Fig. 7 is an elevation partly in section illustrating a carbide cartridge and cartridge holder mounted on a replacing frustum. Fig. 8 is an elevation partly in section of a frustum employed in removing and replacing a carbide cartridge relative to a holder. Fig. 9 is a plan of a portion of a generator showing means for automatically changing the respective positions of two carbide cartridges. Fig. 10 is an elevation of the same.

In the construction of the device as shown the numeral 10 designates a pan, which pan preferably is cylindrical, comparatively shallow and open at its top. A plurality of brackets 11 are fixed to the inner wall of the pan 10 near its top. A water tank 12 of cylindrical form and open at its top is formed of slightly less diameter than the pan 10 and is adapted to be removably mounted on and supported by the brackets 11. A cylindrical gas bell 13 is open at its bottom and preferably made with a conical or dome shaped top, is of slightly less di-

ameter than the tank 12 and is loosely mounted therein. Apertured ears 14, 15 are fixed to and project from diametrically opposite points on the upper periphery of the gas bell 13 and guide rods 16, 17 are mounted loosely through said ears and loosely through apertured ears 18, 19 projecting from the upper portion of the tank 12. The lower ends of the guide rods 16, 17 are threaded and are adapted to be screwed into ears 20, 21 fixed to and projecting from the tank 12 beneath and in vertical alinement with the ears 18, 19 and formed with threaded apertures. Thus provision is made for permitting the gas bell 13 to rise and fall in the water tank 12 but preventing rotary movement of the gas bell relative thereto.

The gas bell 13 is formed with diametrically opposite cylindrical wells 22, 23 extending to the bottom of said gas bell, rising somewhat above its top and open at both ends. An open-ended shell 24 of cylindrical form is removably and replaceably mounted in each well. At least three of these shells 24 should be employed with each generator, the third (not shown) being used as a reserve, and they and the elements carried thereby are alike in construction. A frustum 25 is mounted in and sealed to the lower portion of the shell 24 and tapers upwardly therein for a distance to form an annular water seal 26. Studs 27 are fixed to and project from opposite sides of the shell 24 and are slidingly mounted in vertical slots 28 in the upper portions of the walls of the wells 22 and 23. The cloths 28 extend from the top of the gas bell 13 nearly to the tops of the wells and are formed with horizontal portions 28^a at their upper ends adapted to receive the studs 27 at times to sustain the shells in elevated position in the wells. The studs preferably are provided with knobs or handles 29 on their outer ends.

A cartridge holder 30 of cylindrical form and open at its bottom is fitted snugly within the upper portion of the shell 24 and the lower end of said holder embraces the upper portion of the frustum 25 and enters the water seal 26. The cartridge holder 30 is provided with a handle 31 on its top for convenience in removing and replacing it relative to the shell. A carbide cartridge 32 of cylindrical form and open at its top is loosely mounted within the holder 30 and is of less length than said holder. Springs 33, 34 are fixed to the inner side

of the holder 30 and are inclined inwardly and adapted to engage the bottom of the cartridge 32 to hold the same in place within the holder. Lugs 35 are fixed within and 5 project downwardly from the top of the holder 30 and are adapted to engage opposite sides of the top of the cartridge 32 and center the same relative to the holder. The cartridge 32 is formed with a central 10 hole in its bottom and a collar 36 is sealed to the bottom and circumferentially of said hole and rises within the cartridge. A sleeve 37, open at its ends, is fitted snugly within and is removable relative to the collar 36, and downward movement of said 15 sleeve relative to the collar is limited by a peripheral rib 38 on said sleeve. The sleeve rises nearly to the top of the cartridge 32 and a quantity of carbid 39 is 20 adapted to be contained in said cartridge around said sleeve. A plurality of holes 40 are formed in the lower portion of the cartridge 32 and serve to admit water to the carbid 39. An open-ended frustum 41 25 is sealed to the bottom of the cartridge 32 circumferentially of the hole therein and with its larger end down. It is the function of the frustum 41 to guide and direct the cartridge while lowering the cartridge and 30 its holder over a gas pipe 44 rising within the well.

An open-ended frustum 42 (Fig. 8), is independently formed and is employed in the operation of removing and replacing a 35 cartridge 32 relative to a holder 30. In the removing operation the frustum 42 is placed on a suitable support with its large end up (see Fig. 6). The holder 30 is raised by its handle 31 and superposed relative to the frustum, and then pressed downwardly thereon until the springs 33, 34 are engaged by the upper margin of said frustum and pressed outwardly against the walls of the holder (dotted lines Fig. 6). 40 The lower end of the cartridge 32 enters the open upper end of the frustum 42 and is engaged by an inwardly extending flange 42^a fixed to the inner side of said frustum near its larger end. A sharp upward pull 45 on the handle 31 will then release the holder 30 from the cartridge 32 and leave said cartridge standing on the frustum 42 and supported by the flange 42^a. The cartridge may then be inverted to remove the ash and 50 residuum and be cleaned and recharged. To replace the cartridge 32 in the holder 30 the frustum 42 is placed on its larger end and the cartridge mounted upon it (see Fig. 7), the upper end of the frustum being 55 of less diameter than the cartridge. The holder 30 is then lifted by the handle 31 and lowered over the cartridge and frustum, the springs 33, 34 being pressed outwardly by contact with the walls of the 60 cartridge. When the upper ends of the 65

springs have reached the bottom of the cartridge (dotted lines Fig. 7) they spring into place beneath it and the holder is ready to be mounted in the generator.

Gas pipes 43, 44 are mounted in vertical 70 position in opposite sides of the water tank 12, rise within the wells 22, 23, pass upwardly within the shells 24, through the frustums 25, frustums 41, collars 36 and within the sleeves 37. The pipes 43, 44 75 turn laterally near the bottom of the tank 12 and pass out through and are sealed to the walls of said tank. The pipes 43, 44 terminate in T's 45, 46 just outside the tank 12, which T's contain cut-off valves 80 47, 48 respectively, adapted to be operated by suitable means such as a key or wrench (not shown). From the T 45 pipes 49, 50 lead in opposite directions and then turn laterally and pass through and are sealed 85 to the wall of the tank 12. From the T 46 pipes 51, 52 lead in opposite directions and then turn laterally and pass through and are sealed to the wall of the tank 12. The pipes 49 and 51 meet within the tank 12 90 and are connected by a cross 53; while the pipes 50 and 52 meet within the tank and are connected by a T 54. From the cross 53 a delivery pipe 55 leads laterally and then turns upwardly at the center of the 95 tank and rises above the water line, indicated by the line 56, and within the gas bell 13. A floating valve or controller is loosely mounted on the open upper end of the delivery pipe 55 and comprises a sleeve 100 57 surrounding and slidably on said pipe, a cap 58 mounted over the end of the pipe concentric with said sleeve and fixed thereto by lugs 59, and an annular float 60 fixed to and concentric with the lower portion of 105 said cap. The cap is open at its bottom below the water line 56 and is maintained in such position by the float 60. It is the function of the floating valve or controller to cause gas issuing from the delivery pipe 11 55 to pass through the water in the tank for washing purposes before entering the gas bell 13. A drain pipe 61 also leads from the cross 53 and passes downwardly through and is sealed to the bottom of the 1 tank 12. The drain pipe 61 turns laterally near the bottom of the pan 10 and traverses said pan to a point near its opposite side where it terminates in a T 62. One branch 115 of the T 62 is directed downward toward and in close proximity to the bottom of the pan 10, and is open.

A receiving chamber 63 is mounted in upright position near one side of the water tank 12 and extends upwardly within the gas bell and above the water line 56. The top of the receiving chamber 63 is formed with a plurality of holes 64 to receive gas from the bell 13. The lower end of the chamber 63 preferably is formed with a threaded nip-

ple screwed into a **T** 65 at the bottom of the tank 12 and communicates through said nipple and **L** with a service pipe 66 which passes through and is sealed to the wall of said tank and leads therefrom to a place of use. A drain pipe 67 leads from the **T** 65, passes through and is sealed to the bottom of the tank 12, and connects with the drain pipe 61.

10 A safety pipe 68 leads from the **L** 54 and terminates in a cross 69. A pipe 70 leads upwardly from the cross 69 along one side of the tank 12 and is open at its top on a level with the top of said tank. A tube 71 is fixed to the gas bell 13, preferably by soldering to the inner side of the wall thereof, is open at its bottom, and is adapted to receive loosely the upper portion of the pipe 70. The tube 71 is formed with holes 72 in its side normally below the water line 56. In case the pressure in the bell 13 becomes too great and causes said bell to rise to a point to bring the holes 72 above the water line 56, the excess of gas in said bell will be carried off through said holes 72 and the pipe 70. A pipe 73 is connected to the cross 69, passes through and is sealed to the wall of the tank, and leads to a point of escape to the atmosphere outside any building in which the generator may be located. A drain pipe 74 leads downwardly from the cross 69 through and is sealed to the bottom of the tank 12, and connects with the **T** 62. It is the function of the drain pipes 61, 67 and 74 to prevent the accumulation of water of condensation in the pipes and chambers by conveying such water to the **T** 62 and discharging it at the bottom of the pan 10.

An open lip 75 is fixed to the side of the pan 10 and communicates with the interior thereof by means of holes 76. It is the function of the lip 75 to serve as a means of introducing water to the pan 10 and also to act as a water gage. A lip 77 is fixed to the upper portion of the water tank 12 and communicates with the interior thereof by means of holes 78, and serves a similar purpose with respect to said tank.

In practical use the parts are assembled as shown and charged as described. One of the shells 24 preferably is raised and held by its studs 27 engaging the horizontal portions of the slots 28, out of operative position. The other shell with its contents is lowered in the well, such as 23, and water from the tank 12 enters said shell and rises between the cartridge holder 30 and carbide cartridge 32. Some of the water enters the holes 40 and acts on the carbide 39 to the production of acetylene gas. Gas so generated fills the cartridge 32 and enters the sleeve 37 and pipe 44 (or 43 when the other side is in use). Gas is prevented from escaping from the holder 32 in any other manner by the water seal 26, which is filled with water when the

shell is lowered in its well. Normally the valves 47, 48 are open to the pipes 49 and 51 as indicated in Fig. 3, and gas from the pipes 43, 44 passes therethrough, into the pipe 55 and thence into the gas bell 13 in the 70 manner hereinbefore described. As gas accumulates in the bell 13 said bell is caused to rise on the guide rods 16, 17, and as this movement continues the carbide cartridge is carried out of the water and the production 75 of gas ceases. As gas is used from the bell this movement is reversed and the production of gas is again commenced. Gas is delivered from the bell 13 through the chamber 63 to the service pipe 66. Upward movement of the bell 13 on the guide rods is 80 limited by the action of the safety pipes leading from the tube 71.

When one cartridge 32 is exhausted it may be removed and the other lowered into operative position, or both may be operated at the same time if necessary. It is desirable to have an extra cartridge with its holder to place within the generator as soon as one has been exhausted and during the operation of 85 cleaning and recharging such exhausted cartridge. During the time that one of the cartridges is being removed from the generator it is desirable to turn the valve 47 or 48 connected with the pipes 43 or 44 for communication with the pipes 50, 52. This arrangement permits the inlet of air through the pipes 50, 52 to relieve the partial vacuum created by withdrawal of the cartridge and holder, and facilitates such withdrawal. 90

In the construction illustrated in Figs. 9 and 10 means is provided for automatically shifting the cartridges 32 relative to each other as to operative or inoperative positions in the wells 22, 23. A pin 79 is 105 fixed to and rises from the center of the top of the gas bell 13 and a lever 80 is balanced and supported at its center on the upper end of said pin. The lever 80 is forked at its ends and embraces the wells 110 22, 23, and each fork of said lever is formed with longitudinal slots 81 on both sides in which slots the studs 27 are slidingly received. When both cartridges are full of new carbide one is manually pushed down 115 into the water, which increases the weight thereof and holds it down. As the carbide in the lower cartridge is disintegrated by action of the water and as gas accumulates in said cartridge, it becomes lighter, and by 120 the time the carbide therein is exhausted the equilibrium is overcome and the other or loaded cartridge is caused to descend to operative position.

I claim as my invention—

1. An acetylene gas generator, comprising a water tank open at its top, a gas bell open at its bottom and mounted within said tank, said gas bell being arranged for vertical movement relative to said tank, open-ended 130

wells in said gas bell, carbid cartridges removably and replaceably mounted in said wells, pivoted means connecting said cartridges for maintaining one of said cartridges in inoperative and the other in operative position, gas communication between said wells and gas bell through said tank, and means for drawing gas from said bell.

2. An acetylene gas generator, comprising a water tank, a gas bell mounted in said tank, open-ended wells in said gas bell, shells adjustably mounted in said wells balanced connections between said shells, carbid cartridges removably and replaceably mounted in said shells, said cartridges formed with holes in their bottoms, gas pipes entering said holes and passing down through the shells and communicating with said gas bell, and means for drawing gas from said bell.

3. An acetylene gas generator, comprising a water tank, a bell mounted relative thereto, open-ended wells in said bell, shells formed with studs and slidingly mounted in said wells, vertical slots in said wells, the studs of the shells entering said slots, a lever pivotally mounted and formed with longitudinal slots in its ends engaging said studs carbid containers in said shells, gas communication between the shells and the bell, and means for drawing gas from said bell.

4. An acetylene gas generator, comprising a water tank, a gas bell therein, a well in said bell, said well open at its top above the bell and open at its bottom to said tank, a shell adjustably mounted in said well, a water seal in and carried by the lower portion of said shell, and removable therewith a cartridge holder open at its bottom and

containing a removable cartridge, the lower end of said holder adapted to enter said water seal, said cartridge formed with water ports, gas communication between said cartridge and the gas bell, and means for drawing gas from said bell.

5. An acetylene gas generator, comprising a water tank, a gas bell therein, a well in said bell, said well open at its top above the bell and open at its bottom to said tank, a gas pipe rising through said well and leading to the gas bell, an open-ended shell adjustably mounted in said well, a water seal in and carried by the lower portion of said shell, and removable therewith a cartridge holder open at its bottom and containing a cartridge, the cartridge holder adapted to be mounted in said shell and to enter said water seal, the cartridge formed with means for receiving the upper end of said gas pipe and also formed with water ports, and means for drawing gas from said bell.

6. In an acetylene gas generator, a cartridge holder of cylindrical form and open at its bottom, a carbid cartridge of cylindrical form and open at its top, said cartridge adapted to be mounted within said holder, springs adapted to retain said cartridge in said holder, and means for removing and replacing said cartridge relative to said holder, said means comprising an open-ended frustum.

Signed by me at Des Moines, Iowa, this 30th day of September, 1911.

EDGAR T. WINTER.
